UNITED STATES PATENT OFFICE

168,016

TABLESPOON OR SIMILAR ARTICLE

Jaime Dario Lopez Bermudez, Mexico City, Mexico

Application June 11, 1951, Serial No. 15,500

Term of patent 7 years

(Cl. D44—29)

To all whom it may concern:

Be it known that I, Jaime Dario Lopez Bermudez, a citizen of Mexico and resident of Mexico D. F., Mexico, have invented a new, original, and ornamental Design for a Tablespoon or Similar Article, of which the following is a specification, reference being had to the accompanying drawing, forming part thereof.

Fig. 1 is a top plan view of a tablespoon or similar article, showing my new design.

Fig. 2 is a side view thereof.

Fig. 3 is a bottom plan view thereof.

Fig. 4 is a cross-sectional view taken on line 4—4 of Fig. 1.

Fig. 5 is a cross-sectional view taken on line 5—5 of Fig. 1.

I claim:

The ornamental design for a tablespoon or similar article, substantially as shown.

JAIME DARIO LOPEZ BERMUDEZ.
